(57) **CLAIM**

The ornamental design for a pants, as shown and described.

DESCRIPTION

FIG. 1 is a front perspective view of pants showing our new design in an in-use configuration;

FIG. 2 is a front view thereof;

FIG. 3 is a rear view thereof;

FIG. 4 is a side view thereof;

FIG. 5 is a second side view thereof;

FIG. 6 is a top view thereof; and,

FIG. 7 is a bottom view thereof.

The broken lines immediately adjacent to the shaded area represent unclaimed boundaries of the design. The unshaded regions, demarcated by broken lines, represent unclaimed portions of the pants and form no part of the claimed design. The broken lines showing the remainder of the pants or within the shaded area are for environmental purposes only and form no part of the claimed design.
